UNITED STATES PATENT OFFICE.

CHARLES E. CHAMBERS, OF ASHEVILLE, NORTH CAROLINA.

LOOM ATTACHMENT.

1,395,904.

Specification of Letters Patent.

Patented Nov. 1, 1921.

Application filed July 7, 1919. Serial No. 308,955.

To all whom it may concern:

Be it known that I, CHARLES E. CHAMBERS, a citizen of the United States, residing at Asheville, in the county of Buncombe and 5 State of North Carolina, have invented new and useful Improvements in Loom Attachments, of which the following is a specification.

This invention relates to looms and has 10 for its object the provision of novel means for attaching the check strap which passes around the picker stick for the purpose of stopping the travel of the shuttle.

Another object is to provide means for 15 securing the check strap in a manner to permit of adjustment so as to properly position and regulate the length of the strap.

A further object is to provide a strap attaching means, by which the length of the 20 strap necessary for the proper operation of the shuttle is materially reduced, thereby resulting in a saving of material, especially where a number of looms are in operation.

Other objects and advantages of the 25 invention will appear as the following description is read in connection with the accompanying drawings.

In the drawings:

Figure 1 is a bottom plan view of the 30 magazine end of the loom lay illustrating the arrangement of the check strap and its securing clamp and the manner of attaching the same to the loom.

Fig. 2 is a side elevation of the subject 35 matter of Fig. 1.

Fig. 3 is a longitudinal sectional view through the clamp, with the ends of the strap in position.

Fig. 4 is a detail perspective view of the 40 clamp plate used at the magazine end of the lay.

Referring to the drawings in detail, wherein like characters of reference denote corresponding parts, the lay is indicated at 45 10 and is provided with the usual slot 11, for the passage of the picker stick 12, a fragmentary portion of the shuttle box being indicated at 13. These elements may be of the usual or any preferred construction 50 and form no part of the present invention, which resides in the manner of attaching the check strap which passes around the picker stick 12 in the usual manner, said strap being indicated at 14.

55 As before stated, the invention resides in the manner of securing the strap 14 to the

loom, and for this purpose there is provided at each end of the lay a bracket 15, which may be of any suitable construction and secured in position by any desired means. 60 Secured to each of the brackets is a clamp 16, the clamp at the magazine end of the loom being formed of a plate 17. This plate has substantial parallel side edges and is provided intermediate its end with a longitudinally disposed slot 18, for the passage of a bolt or stud and by means of which it is secured to the bracket 15. The plate is curved at each end, and these ends are rounded as at 20, and are provided with 65 longitudinally disposed slots 21. Each end of the strap 14 engages over the rounded ends 20 of the plate and is clamped between said plate and a clamping strip 22, which is adjustably secured to the plate through the 70 medium of a bolt 23, which passes through the slot 21 and through an opening 24 in the strip 22. These strips are provided along one edge with a bead 25, so that a portion of the strips is spaced from the plate for the 75 reception of the ends of the strap 14.

By means of the slot 18, the plate may be properly positioned with respect to the picker stick, while the slot 21 provides for the proper adjustment in the length of 80 the strap.

The clamp 16 at the opposite end of the lay is in all respects similar to the clamp just described, except that the plate which is indicated at 26, has its central slot 27 85 offset from the end slots 21, so that to provide for this one longitudinal edge of the plate is offset, as indicated at 28.

By the use of the improved clamp, the 90 material reduction in the length necessary for the strap is obtained, the strap now in use being from twenty-two to twenty-three inches in length, while the strap used in connection with the herein described clamp is about sixteen inches in length, so that 95 in the initial installation the saving of six or seven inches of leather is effected, and when the strap becomes worn, the loss is considerably less than in the former strap. Further, by securing the strap to one side 100 of the lay, a side pull is exerted upon the picker stick which results in more gradual check of the shuttle and relieves to an appreciable extent pressure of the springs and the shuttle pointer and adds to the life of 105 the shuttle. In addition this gradual check eliminates a sudden jar and pull upon the 110

strap at the end of the stroke and therefore adds to the life of the strap.

The invention is susceptible of various changes in its form, proportions and minor details of construction and the right is herein reserved to make such changes as properly fall within the scope of the appended claims.

Having described the invention, what is claimed is:

10. 1. A picker check for looms comprising a flexible loop extending around the picker stick, a plate adjustably secured to one side of the lay and means for securing the loop to the plate, whereby a side pull will be exerted upon the picker stick at the end of its stroke.
15. 2. A picker check for looms comprising a strap extending around the picker stick, an elongated plate secured to one side of the lay and means located at each end of the plate for securing each end of the strap to provide a loop, whereby a side pull will be exerted upon the picker stick at each end of its stroke.
20. 3. A picker check for looms comprising

a strap extending around the picker stick, a plate secured to one side of the lay and transversely curved clamping strips adjustably secured to each end of the plate for securing the ends of the strap to provide a loop, whereby a side pull will be exerted upon the picker stick at the end of its stroke.

4. A picker stick for looms comprising a strap extending around the picker stick, a curved plate having a longitudinally disposed slot intermediate its ends for adjustable attachment to one side of the lay, curved rounded ends for said plate, said curved rounded ends also being provided with longitudinally disposed slots, clamping strips for securing the ends of the strap to each end of the plate and clamping bolts passing through the last mentioned slots and engaging the clamping plates and strap, whereby a side pull will be exerted upon the picker stick at each end of its stroke.

In testimony whereof I affix my signature.

CHARLES E. CHAMBERS
